[57] CLAIM

The ornamental design for an adjustable support stand for a musical instrument, as shown and described.

DESCRIPTION

FIG. 1 is a front perspective view of an adjustable support stand for a musical instrument showing my design; FIG. 2 is a view of the musical instrument stand of FIG. 1, taken from the front of the stand;

FIG. 3 is a view of the musical instrument stand of FIG. 1, taken from the back of the stand;

FIG. 4 is a view of the musical instrument stand of FIG. 1, taken from the left side of the stand;

FIG. 5 is a view of the musical instrument stand of FIG. 1, taken from the right side of the stand;

FIG. 6 is a view of the musical instrument stand of FIG. 1, taken from the top of the stand; and

FIG. 7 is a view of the musical instrument stand of FIG. 1, taken from the bottom of the stand.

FIG. 1

FIG. 6

FIG. 2

FIG. 5

FIG. 3

FIG. 4

FIG. 7
